UNITED STATES PATENT OFFICE.

THEODORE HOHAUS, OF WINONA, MINNESOTA, ASSIGNOR TO UNION FIBRE COMPANY,
OF WINONA, MINNESOTA, A CORPORATION OF MINNESOTA.

MACHINE FOR MAKING FIBER INSULATING-SHEETS.

1,105,786.

Specification of Letters Patent.

Patented Aug. 4, 1914.

Application filed August 19, 1912. Serial No. 715,701.

To all whom it may concern:

Be it known that I, THEODORE HOHAUS, a citizen of the United States, residing at Winona, in the county of Winona and State 5 of Minnesota, have invented certain new and useful Improvements in Machines for Making Fiber Insulating-Sheets, of which the following is a specification.

My invention relates to improvements in 10 machines for making insulating sheets of fiber, having special reference to flax or other vegetable fibers, its object being to provide improved mechanical means for distributing and interlacing the fibers, where- 15 by to produce a more perfect and uniform entanglement and distribution of the same, so that the sheet will be more uniform in structure and thickness, more coherent and pliable, and have greater strength. In the 20 product so produced there will be practically no wastage, because of the uniform thickness and structure of the sheets.

Insulating sheets of fiber are usually made by delivering the fibrous material upon a 25 traveling apron, which first carries the same through water in a tank where the fibers are distributed and interlaced, and then under or between a succession of such compression instrumentalities as rolls and tampers 30 to squeeze out the water and complete the felting of the fibers.

Heretofore in the art the distribution and interlacing of the fibers has been done by manual labor, the workmen standing at 35 the sides of the tank at the point where the fibers are carried into the water, and distributing and interlacing them in the water with their fingers. When done in this way it is obviously impossible to secure an even 40 distribution or uniform entanglement of the fibers, so that the sheets produced have many imperfections of structure and irregularities in thickness and finish. To overcome these imperfections I have devised the im- 45 proved mechanical distributing and interlacing instrumentalities hereinafter described.

More particularly my invention consists in the construction, combination, and ar- 50 rangement of parts hereinafter described and claimed.

In the accompanying drawings showing the preferred embodiment of my invention,

Figure 1 is a top view of the improved ma- 55 chine; Fig. 2 is a longitudinal section through the same on line $x-x$ of Fig. 1; Fig. 3 is a cross section on line $y-y$ of Fig. 2, showing one of the interlacing cylinders; Fig. 4 is a longitudinal section through one of the interlacing cylinders on line $z-z$ of 60 Fig. 2; Figs. 5 and 6 are side and bottom views, respectively, of the acting face of one of the first pair of tampers; Fig. 7 is a plan view of the foraminous slats of the apron or conveyer; and Fig. 8 is a cross section 65 through the same on line $w-w$ of Fig. 7.

The machine here shown is designed es- 70 pecially to handle flax fiber and embodies a relatively long tank 2 supported upon the frame A. Within the tank runs the upper 70 reach of an endless traveling apron or conveyer formed by side chains 3 and trans- 75 verse slats 4, the slats having, preferably, a large number of holes 5 to permit water to pass through.

In the structure here shown the apron 80 passes over an idler roller 6 at the feed end of the machine and over rollers 7 and 8 at the forward or delivery end of the machine. It is shown driven from the main drive 80 pulley B by means of the following mech- 85 anism: Fast upon the shaft of this drive pulley is a gear 9 which meshes with a gear 10 upon the shaft of the large roller 7. At each end of this roller is a sprocket 11 which 85 engages and coacts with the corresponding side chain 3 of the conveyer, whereby to drive the same. It will be seen that the conveyer does not wrap around the roller 7 or its sprockets 11, but its upper reach 90 merely rests upon the roller and sprockets and then passes on and wraps about the smaller roller 8. This roller is driven from the shaft of the roller 7 by means of sprocket 95 and chain connection 13. The roller 8, be- 95 ing of smaller diameter than the roller 7, will move faster and exert a constant pull upon the apron, the sprockets of the roller 7 serving both to pull the upper reach of the belt through the tank and also to push it 100 along toward the smaller roller 8. This arrangement serves to keep the belt under constant and uniform tension, and prevents the chains from being shaken or slipping off the sprockets 11.

The material, which may consist of wholly

or partially degummed and washed fibers of flax, may be delivered upon the top reach of the traveling apron before the same enters the water in the tank by any convenient feeding means. In the drawings I have shown a feeder substantially like that covered by United States Letters Patent No. 828,403, issued to me on August 14, 1906. As the feeder forms no part of the present invention it will be sufficient to say that the material passes from the hopper 14 to a traveling belt 15, whence it is picked up by the pins of a rotating drum 16 and carried upwardly and forwardly with the drum, the surplus material being removed from the drum and driven into a chute 17 by means of the pins upon a doffer 18, these pins traveling in proximity to the pins upon the drum 16, but in a reverse direction. The material remaining on the drum 16 is then carried forwardly until it is caught by the pins of a second doffer 19 which run in proximity to the pins on the drum 16 and in the same direction. The fiber is picked off the drum by this doffer and delivered in loose condition upon the top reach of the apron before the same enters the tank.

At the point where the apron enters the tank its side chains pass over, and drive, the idler sprockets 20 of a shaft 21 journaled in the side walls 53 of the tank, and then down and under the under-running sprockets 22 upon the shaft of a roller 23, also journaled in the side walls of the tank, thereby driving the sprockets 22 and the roller 23 fast upon the shaft thereof. The sprockets 20 are arranged near the top of the tank, so as to keep the apron out of contact with the edge of its rear end-wall, and in close proximity to the submerging sprockets 22, which carry the apron downward into the water in the tank, as best shown in Fig. 2. The roller 23 is preferably fluted or ribbed transversely to its direction of rotation, whereby to grip and hold the fiber until the same has been carried beneath it, the pressure of the moving fiber against the ribs or corrugations of the roller also assisting to drive the same. Near the forward end of the tank is another submerging instrumentality, which may consist, as here shown, of a pair of idler sprockets 24 journaled in the side walls 53 of the tank in position to be engaged by the side chains of the apron. Between the two submerging instrumentalities, which are positioned near the opposite ends of the tank, are arranged the fiber interlacing instrumentalities which are more particularly the subject of this invention. As here shown these instrumentalities consist of a series of under-running cylinders D, D¹, and D² having their peripheries studded at frequent intervals with pins 25 which project backwardly from the direction of travel of

the cylinders, preferably at an angle between the radial and tangential angles, the cylinders being arranged so that the pins upon each cylinder will travel in close proximity to the pins on the next succeeding cylinder. These cylinders run in the direction indicated by the arrow in Fig. 2 and may be driven in any convenient way, either by the apron or by an independent source of power. It is important, however, that the speed of travel of the pins at about their medial point should be substantially the same as the speed of travel of the apron, so that the pins will move with the fiber. As here shown the cylinders are driven from the shaft 26 of the fluted roller 23, which is itself driven by the apron, in the following manner:

Upon the end of the shaft 26 which projects beyond the side wall of the tank are a pair of sprockets 27 and 28. The sprocket 27 has chain connection 29 with a sprocket 30 upon the projecting end of the shaft of the forward cylinder D², while the sprocket 28 has chain connection 31 with a sprocket 32 upon the projecting end of the shaft of the middle cylinder D¹. The rear cylinder D is driven from the shaft of the forward cylinder D² by means of a chain 33 which passes over sprockets upon the shafts of both of these cylinders. All of these sprockets are of such size that the speed of travel of the cylinder pins at their middle point will be the same as the speed of travel of the apron. In order that the fibers may be intertwined and interlaced by the pins of these cylinders, the cylinders are also given an axially reciprocatory motion transversely of the tank. In the embodiment of the invention shown in the drawings this is accomplished in the following manner: Each of the cylinders is keyed upon a sleeve 34 which is feathered upon the shaft 35 thereof, as indicated at 36 in Fig. 4, so as to be capable of longitudinal or axial movement upon the shaft. The reciprocatory movement may be imparted to these cylinders by any convenient mechanism. As here shown they are driven from a drive pulley C, the shaft of which is journaled in the sides of the tank. On one end of this shaft is a bevel gear 37 which meshes with a bevel gear 38 upon the eccentric shaft 39 supported in suitable bearings 40 upon the outside of the tank. The adjacent ends of the sleeves 34 of each of the cylinders D, D¹, and D² are journaled in the eccentric straps 41, so that they will be free to rotate therein, and will also be reciprocated by the eccentric when the eccentric shaft 39 is turned. The eccentrics for the cylinders are mounted so as to travel at suitable distances apart, the arrangement here shown being such that the eccentric for each cylinder will travel one-third in advance of

the eccentric for the next succeeding cylinder, whereby to give the cylinders oppositely directed or cross movements at variable rates of speed, and thereby enable the cylinder pins to effect as complete an entanglement and interlacing of the fibers as possible. The water in the tank is kept from rising above a proper level, such as that shown in Fig. 2 of the drawings, by means 10 of an overflow opening 42. It will be seen that the interlacing cylinders are so mounted that the pins only will be submerged in the water, and that the pins leave the water at a downward and forward angle 15 so as not to pull the fiber up with them.

It will be seen that the forward roller 7 over which the apron passes is positioned above the level of water in the tank, so that the apron after it leaves the submerging 20 sprockets 24 will travel upwardly and leave the water before it reaches the end of the tank. Just at and beyond the point where it emerges from the water are arranged suitable instrumentalities for compacting the 25 intertwined fibers and expelling the water therefrom, this water escaping through the holes 5 in the foraminous slats. The compression devices here shown comprise a series of tampers. The rear tampers 43 are hung 30 upon eccentrics 44 and their operating faces consist of V-shaped ribs 45. The apices of the ribs on one of these tampers are directed toward one side of the tank, while apices of the ribs on the other tamper are directed 35 toward the opposite side of the tank, whereby to effect a complete working of all parts of the material. Forwardly of these is a third tamper 46 hung upon an eccentric 45, the acting face of which preferably consists 40 of two ribs extending transversely to the line of travel of the apron. All these eccentrics may be driven from any suitable source of power (not shown). From these tampers the apron carries the material between the 45 roller 7 and the coating press roller 47 mounted in spring pressed bearings 48 and driven from any suitable source of power. After the sheet has been carried through the 50 rollers 7 and 47, it is delivered from the apron to press rolls 49 and 50, which may be driven from any suitable source of power. From these press rolls it passes on to a suitable table or conveyer 51.

The shock of the reciprocatory endwise movement of the interlacing cylinders may be taken up, if desired, by means of coil springs 52 interposed between the cylinders and the side walls of the tank, as best shown in Fig. 3. The lower reach of the apron is 55 supported in its return travel underneath the tank by means of a deck 54 carried by the framework of the machine.

In use the fibrous material, which is usually in somewhat wet and matted condition is deposited upon the top reach of the

apron before the same has become submerged in the water in the tank. This may be done by any convenient mechanism or other means, such, for instance, as the feeding and doffer devices shown in the drawings and described above. The apron as it enters the tank is carried down beneath the water by the sprockets 22 and roller 23, and is kept submerged by these instrumentalities and the rotary sprockets 24 during a considerable portion of its travel through the tank. The fibrous material is carried under the water with the apron, being held against the apron by the roller 23 until it has passed this roller and is in proximity to the first interlacing cylinder D. At this point, being now relieved of the pressure of the roller 23, the fibrous material rises in the water and the fibers become somewhat loosened and separated. In this condition the fibers are immediately subjected to the combined rotary and crosswise reciprocatory movements of the pins upon the interlacing cylinders, whereby the fibers are crossed, interlaced, and pretty evenly distributed throughout the width of the apron. As soon as the fibers have been propelled beyond these cylinders and before they have had an opportunity to become disentangled, the apron carries them up out of the water and under such compression instrumentalities as may be selected to complete the felting. The instrumentalities here shown are the tampers 43 and 46, which are hung upon eccentrics, and exert a rapid and constant pounding against the interlaced material, thereby expelling the water therefrom through the foraminous slats and compacting the material into a continuous sheet, the acting faces of the tampers 43 being constructed with oppositely directed V-shaped ribs as above described in order to effect a pounding and compressive action upon practically every part of the sheet.

After the material has been carried past the tampers it is carried through the squeeze rolls 7 and 47 as above described, whence it is delivered from the apron as a self-sustaining sheet to a second pair of squeeze and finishing rolls 49 and 50, to be finally discharged upon a suitable table 51. In the sheets so formed the fibers are so completely interlaced and intertwined, and are so evenly distributed, that all parts of the sheet are of practically uniform thickness and texture, and there are no soft spots resulting from imperfect distribution of the fiber, which would impair the insulating properties of the sheet. For this reason there is practically no wastage, and the sheets are highly resilient and self-sustaining. The uniformity of texture, structure, and thickness makes the sheets particularly desirable for heat insulating purposes in refrigerator cars and the like, where spots of defective insulation greatly impair the usefulness of the product.

By the term "water," as used in the claims I mean to include any liquid which will allow the fibers to be handled and formed into sheets in substantially the manner herein described.

I claim as my invention:

1. In a machine for making fiber insulating sheets, the combination with a submerged traveling apron operative to carry the fibrous stock through the water to a point above the same, of means working in the water and moving transversely across the line of travel of the apron and adapted to distribute and interlace the fibers in their progress through the water, and means operating upon the interlaced fibers to compact and expel water from the same.
2. In a machine for making fiber insulating sheets, the combination with a submerged traveling apron adapted to carry the fibrous stock through and out of the water, of crosswise reciprocating elements working in the water across the line of travel of the apron and adapted to distribute and interlace the fibers in their progress through the water, and compression elements operative upon the thus interlaced fibers, whereby to compact the same and expel water therefrom.
3. In a machine for making fiber insulating sheets, the combination with a submerged traveling apron operative to carry the fibrous stock through and above the water, of means working in the water and having both a rotary movement in the direction of the line of travel of the fibers and also a reciprocating movement across the line of travel thereof, whereby to distribute and interlace the same, and compression devices acting upon the thus interlaced fibers.
4. In a machine for making fiber insulating sheets, the combination with a submerged traveling apron operative to carry the fibrous stock through the water to a point above the same, of a multiplicity of pins having a reciprocating movement in the water across the line of travel of the fibers, whereby to distribute and interlace

the same, and having also a rotary movement in the line of travel of the fibers.

5. In a machine for making fiber insulating sheets, the combination with a submerged traveling apron operative to carry the fibrous stock through the water and to a point above the same, of a multiplicity of pins or fingers working oppositely in the water at variable rates of speed across the line of travel of the fibers whereby to distribute and interlace the same, said fingers having also a rotary movement in the direction of the line of travel of the apron.

6. In a machine for making fiber insulating sheets, the combination with a submerged traveling apron operative to carry fibrous stock through the water to a point above the same, of cylinders rotating in the line of travel of the apron and having also an endwise reciprocating movement across the line of travel of the apron, said cylinders being studded with a multiplicity of pins adapted to work within the water and upon the fibers in their progress through the same, whereby to distribute and interlace the fibers.

7. In a machine for making fiber insulating sheets, the combination with a water-containing tank, of an endless foraminous conveyer apron traveling from a point above the water to a point below the water and thence to a point above the same, means for delivering fibrous stock upon the conveyer before the same enters the water, a corrugated roller coacting with the apron at the point where it enters the water to submerge the fibers, and forwardly rotating and transversely reciprocating elements adapted to distribute and interlace the fibers after they have passed from said submerging roller.

In testimony whereof I affix my signature in presence of two witnesses.

THEODORE HOHAUS.
